[57] CLAIM

The ornamental design for a micro-feeder tube for plant injection device, substantially as shown.

DESCRIPTION

FIG. 1 is a perspective view, taken from the top, rear and right side of a micro-feeder tube for plant injection device, showing my new design;

FIG. 2 is a left side elevational view thereof;

FIG. 3 is a front elevational view thereof;

FIG. 4 is a rear elevational view thereof; and

FIG. 5 is a side elevational view thereof taken along line 5—5 of FIG. 3.
